UNITED STATES PATENT OFFICE.

FRED C. HOWE, OF NEW HAVEN, CONNECTICUT.

PORTABLE FAN.

1,254,042.

Specification of Letters Patent. Patented Jan. 22, 1918.

Application filed September 24, 1914. Serial No. 863,366.

To all whom it may concern:

Be it known that I, FRED C. HOWE, a citizen of the United States of America, residing in the city and county of New Haven, State of Connecticut, have invented certain new and useful Improvements in Portable Fans, of which the following is a specification.

This invention relates to portable fans, 10 and aims to provide improvements therein.

The fan of the present invention is intended principally for personal use, and provides a portable fan which is adapted to be conveniently held or carried in the hand, or set 15 upon a convenient object, such as a table or a shelf. The invention, furthermore, provides a device which is simple, efficient, and cheaply manufactured.

The device is preferably self-contained, 20 having an electric cell or battery in the handle thereof.

Other features of improvement will be hereinafter set forth.

An embodiment of the invention is illustrated in the accompanying drawing, wherein—

Figure 1 illustrates the device in side elevation, with the parts in position most convenient for hand use;

Fig. 2 illustrates the device partly in side elevation and partly in longitudinal section, the parts being shown in the position most convenient for setting upon a table or the like; and

Fig. 3 is a front view of the device, the protecting casing in front of the fan being shown in section.

Referring to the drawings, numeral 1 designates a motor-driven fan, comprising a fan 20 2 preferably of the propeller type, and 3 any suitable electric motor for driving the same. The motor is preferably inclosed in a casing 4, and the fan is preferably provided with a wire guard or casing 5. The fan is preferably directly mounted upon the shaft of the motor. The fan, the motor, and also the casing, when present, are compactly arranged, so that the whole constitutes a compact unit.

6 designates a handle, which is adjustable with relation to the motor-driven fan 1. To this end the motor casing may be provided with a stud 7, and the handle provided with a bifurcated stud 8, the two studs being held together by a pivot pin 9 passing through

them, and having a binding screw 10 on one end adapted, when tightened, to bind the parts against movement. By loosening the nut 10, the handle 6 may be turned upon the pivot 9 to a suitable position with relation 60 to the fan, and the nut tightened so as to hold the handle in the desired adjusted position.

Means are preferably provided for supporting the device in such manner that the 65 fan may direct the current of air produced thereby outwardly when the device is set upon a table or the like. This means is preferably a pair of legs 11 the inner sides of which preferably have a contour corresponding to the underside of the casing, and are preferably adapted to turn up and around the underside of the casing when the legs are not desired for assisting in supporting the device. The legs are preferably pivoted upon the same pin 9 as the handle, and are adapted to be clamped in position by the binding screw 10. When it is desired to set the fan upon a table or the like, the handle is turned preferably to the position shown 70 in Fig. 2, and the legs 11 are turned down beneath the fan, the clamping screw 10 being turned to hold the parts in this position. When set upon a table the fan will have a position wherein the fan is upright. The 75 handle and legs are, furthermore, capable of being adjusted in such manner that the fan may be pointed up or down to some extent.

The handle 6 is preferably made hollow and adapted to receive an electric cell 14. 90 The cell 14 may connect with one side of the motor circuit through a contact 15, and may contact with the other side of the motor-circuit through a make and break device 16, and the framework of the device on this 95 side of the motor circuit may be grounded.

The make and break device 16 is preferably in the form of a disk or wheel having a conducting segment 17. By rotating the disk 16 until the segment 17 thereof is in 100 contact with the shell of the cell, a circuit is made. The circuit may be maintained without further action upon the part of the user. When it is desired to break the circuit, the disk 16 is turned until the segment 17 is 105 out of contact with the cell. The handle 6 is preferably provided with a removable portion 18, to permit the replacement of cells.

Modifications may be made in the structure illustrated and specifically described 110

2
without departing from the spirit of the invention.

What is claimed is:—

- 5 1. A portable fan, comprising a motor-driven fan, a handle, and feet, adapted, in conjunction with said handle, to form a support for said fan.
- 10 2. A portable fan, comprising a motor-driven fan, a handle, and feet, said feet being adjustable, and being adapted, in conjunction with said handle, to form a support for said fan.
- 15 3. A portable fan, comprising a motor-driven fan, a handle adjustable with relation thereto, and feet, adapted, in conjunction with said handle, to form a support for said fan.
- 20 4. A portable fan, comprising a motor-driven fan, a handle adjustable with relation thereto, and feet, said feet being adjustable, and being adapted, in conjunction with said handle, to form a support for said fan.
- 25 5. A portable fan, comprising a motor-driven fan, a handle, and feet, adapted, in conjunction with said handle, to form a support

port for said fan, said feet being adapted to be turned up under the lower side of said fan.

6. A portable fan, comprising a motor-driven fan, a handle adjustable with relation thereto, and feet, said feet being adjustable, and being adapted, in conjunction with said handle, to form a support for said fan, and means for fastening said feet and handle in the adjusted positions thereof. 30 35

7. A portable fan, comprising a motor-driven fan, a casing therefor, a handle, and feet, adapted, in conjunction with said handle, to form a support for said fan, the inner side of said feet having a contour corresponding to a side of said casing and adapted to be turned up around said casing when not in use. 40

In witness whereof, I have hereunto signed my name in the presence of two subscribing witnesses.

FRED C. HOWE.
